UNITED STATES PATENT OFFICE.

JOHN G. CALLAN, OF LYNN, MASSACHUSETTS, ASSIGNOR TO GENERAL ELECTRIC COMPANY, A CORPORATION OF NEW YORK.

REGULATING MECHANISM FOR ELASTIC-FLUID TURBINES.

No. 820,911.

Specification of Letters Patent.

Patented May 15, 1906.

Application filed February 23, 1905. Serial No. 246,858.

To all whom it may concern:

Be it known that I, JOHN G. CALLAN, a citizen of the United States, residing at Lynn, in the county of Essex, State of Massachusetts, have invented certain new and useful Improvements in Regulating Mechanism for Elastic-Fluid Turbines, of which the following is a specification.

The present invention relates to improvements in regulating mechanism for elastic-fluid turbines, and has for its object to provide a governing mechanism which will effectively regulate the admission of steam or other elastic fluid to the bucket-wheels and which will shut off the admission of motive fluid to the turbine when the speed of the shaft exceeds a predetermined amount.

In the accompanying drawings, which illustrate one embodiment of my invention, Figure 1 is a partial longitudinal section of a turbine; Fig. 2, a detail view taken on line 2 of Fig. 1 looking in the direction of the arrow; Fig. 3, a partial section taken on line 3 of Fig. 1 looking in the direction of the arrow. Fig. 4 is a detail view showing the means for attaching the emergency-trigger to the valve-actuating mechanism. Fig. 5 is a perspective detail view of the means employed to connect the valve-stem with the governor-actuated lever. Fig. 6 is a partial view, in side elevation, of the bell-crank lever for actuating the valve-stem. Fig. 7 is a bottom plan view of the same. Fig. 8 is a partial side view of the lever, showing the parts in the position which they occupy after the emergency-governor has been operated; and Fig. 9 is a detail view of an improved form of emergency-governor.

1 represents the main shaft, which carries 40 the bucket-wheel 2, the latter being provided with one or more rows of peripheral or other buckets 3. The wheel is inclosed in a casing 4, that is suitably constructed. Where two or more rows of wheel-buckets are employed, 45 intermediate buckets 5 are provided which are located between the adjacent row of the wheel-buckets. These buckets are carried by the support 6, that is bolted to the wheel-casing. Steam or other elastic fluid is admitted through the bucket-wheel by the nozzle 7, which is provided with one or more

fluid-discharging passages which may be expanding or non-expanding in character. They are preferably closely associated, so as to discharge the fluid jet in the form of a 55 solid column.

Mounted on the end of the shaft is a governor or speed-responsive device 8, which is inclosed by the casing 9, the latter being detachable and bolted to the wheel-casing. In 60 order to prevent fluid from leaking from the wheel-casing into the governor-casing, a suitable packing 10 is employed having means for adjusting it.

Bolted or otherwise secured to the face of 65 the wheel-casing is a valve-casing 11. Extending vertically through the valve-casing is a cylindrical bore which is closed at its lower end by a plug 12. The upper end of the bore is closed by a head 13, which contains an oil or grease containing chamber 14, the latter being closed by a removable cover 15. Extending vertically through the center of the plug is a tubular valve-stem 16, and mounted on the stem is a combined regulating and shut-off valve 17 of suitable construction. In the present form of the invention 70 the valve is shown to be of the balanced-piston type, which is suitably guided by the walls of the cylinder. Steam or other elastic 75 fluid is admitted by the conduit 18. The head of the piston-valve is provided with one or more openings to balance the pressure on opposite sides thereof. The opening or openings are so arranged that when the valve is 80 seated—i. e., in its raised position—they are closed by the solid annular portion of the valve-seat.

The upper end of the valve-stem 16 is provided with grooves to restrict the leakage of 90 motive fluid as much as possible. Any steam which escapes around the stem is condensed in the lubricant-containing chamber 14, the latter being filled with asbestos or similar material, and the lubricant is thus 95 caused to rise and flow down through the center of the valve-stem into the chamber 19, located near the lower end thereof, and thus lubricate the valve-stem at the point where it passes through the plug 12. The excess 100 water and lubricant is fed by the passage 20 back into the wheel-casing.

The governor or speed-responsive device comprises a suitable frame 21, upon which are mounted weights 22, the movements of the latter being opposed by a suitable spring. Motion is transmitted from the speed-responsive device to the valve-stem by a bell-crank lever 23 and a connecting-rod 24. Between the connecting-rod and the lever is a bearing 25 or suitable construction, which in the present form of the invention is shown as being of the ball-and-socket type. This bearing is provided with suitable adjusting means and is lubricated by a wick 26, that receives oil from the oil-cup 27. The bell-crank lever is made in two principal parts, 28 and 29, which are provided with a common fulcrum 30, the said fulcrum being carried by a bracket 31, as best shown in Figs. 1 and 2. This bracket is formed integrally with or attached to the valve-casing. Connecting the parts 28 and 29 of the bell-crank lever is a flat spring 32, which normally tends to move the parts to the position shown in Fig. 8. This tendency of the two parts to move independently of each other is normally opposed, however, by a trigger 33, which is provided with a lip 34, that engages with a projection 35 on the horizontally-extending portion of the lever 28, as best shown in Fig. 3. The trigger is carried by the portion 28 of the bell-crank lever and is so supported that it has a certain freedom of movement to permit of its being moved by the emergency-governor to disengage the lip 34 from the projection 35. This construction is best shown in Fig. 4. Referring to this figure, 36 represents a knife-edge which engages a seat 37, having a V-shaped groove in its upper surface. The trigger is secured to the lever 29 by rivets or other means 38, which are rigidly secured to the lever and make a loose fit with the trigger. To state the matter in a different way, the knife-edge 36 and the block 37 form a pivot for the trigger 33, which permits of a certain amount of movement of the trigger either to engage or disengage the lip 34 and the projection 35.

Mounted upon the frame 21 of the speed-responsive device are one or more flat springs 39 under a definite tension which constitutes an emergency-governor responsive to speed changes. These springs are so set that they normally occupy the position shown in Fig. 3; but when the speed of the shaft increases above a predetermined maximum the free ends thereof move outwardly and strike the trigger 33. When the trigger is struck, its lower end is moved to the right, Fig. 3, which permits the parts of the bell-crank lever to separate and assume the position shown in Fig. 8. This separation of the levers is due to the action of the flat spring 32. As this separation takes place the valve-stem 16 is moved upward, which causes the piston-valve 17 to enter the portion of the cylinder

located directly above it, to establish contact with the flat seat at the upper end of this portion and to thereby cut off all communication between the inlet pipe or conduit 18 and the nozzle or other fluid-discharge device or devices. From the foregoing it will be seen that the valve 17 has two seats, one formed by the cylindrical bore, the other by the perforated disk-like portion at the lower end of the head 13. When the valve is closed, the unbalanced pressures thereon hold it against the disk-like seat. In opening the valve the usual practice is to first cut off the supply through the conduit 18. In order to permit the bell-crank lever to move the valve 17 without cramping either in the normal controlling of the turbine or under emergency conditions, the left-hand end of the portion 28 of the bell-crank lever is provided with jaws 40, Fig. 5, which are adapted to receive the pin 41, the latter being provided with flat ends which are free to slide in the jaws. The lower end of the valve-stem 16 is provided with an eye which is located between the jaws, and the pin 41 retains the parts in place. I may employ equivalent arrangements for this purpose.

Under normal operating conditions the speed-responsive device 8 moves the connecting-rod 24 in the direction of the arrow under an increase of speed and in the opposite direction under a decrease in speed. When for any reason the speed of the shaft exceeds a predetermined number of revolutions per unit of time, the free end of the spring or springs 39 moves outwardly and engaging the trigger releases the lock or latch 34 and permits the parts of the bell-crank lever to separate and the valve 17 to close. (In order to reset the mechanism after the emergency-governor has operated the supply of steam to the pipe 18 is cut off, the cover or cap 15 is removed and the stem 16 depressed by a suitable means until the parts of the bell-crank lever are locked by the lip 34 and the projection 35, as shown particularly in Figs. 1, 3, 6, and 7, after which the cap 15 is replaced and the machine started in the usual way.)

In Fig. 9 is shown an improved form of emergency-governor. Each of the springs is mounted in a stud 42 and normally rests on the pin 43 under a stress which may be more or less great. The spring is provided with a relatively long loop or turn 44, and the parts are so arranged that after the spring or springs have achieved their normal travel further outward movement at the given speed is prevented by contact of a point on the spring with its supporting-stud. The full-line position shows the normal position and the dotted line the abnormal.

My invention can be used with the so-called "jet" turbines, also with the so-called

"reaction" turbines, or with any other type of motor wherein it is desired to control the admission of elastic fluid to the moving element.

5 In the drawings stationary and rotary buckets are shown; but I may employ buckets which are all movable.

In accordance with the provisions of the patent statutes I have described the principle 10 of operation of my invention, together with the apparatus which I now consider to represent the best embodiment thereof; but I desire to have it understood that the apparatus shown is only illustrative and that the invention 15 can be carried out by equivalent means.

What I claim as new, and desire to secure by Letters Patent of the United States, is—

1. In a governing mechanism for fluid-actuated motors, the combination of a combined controlling and shut-off valve, a speed-responsive device which moves the valve to and fro to regulate the admission of fluid, and a second speed-responsive device which acts independently of the first to shut the 25 valve when the speed of the motor exceeds a predetermined amount.

2. In a governing mechanism, the combination of a combined controlling and shut-off valve for controlling the admission of motive 30 fluid to the turbine, a speed-responsive device connected to the valve for normally regulating the admission of fluid to the buckets, and a means for breaking the connection between the valve and device and shutting the 35 valve to cut off the supply of motive fluid when the speed of the turbine exceeds a predetermined amount.

3. In a governing mechanism, the combination of a combined controlling and shut-off 40 valve for regulating the admission of fluid to the turbine, a stem for actuating the valve, a speed-responsive device, a divided connection between the valve and said device, and a means for separating the parts of the connection and shutting the valve under predetermined conditions.

4. In a governing mechanism, the combination of a valve regulating the admission of motive fluid to the turbine, a speed-responsive device, a divided connection for transmitting motion from the device to the valve, a lock for uniting the parts of the connection, and a means for releasing the lock under certain predetermined conditions.

5. In a governing mechanism, the combination of a valve, a speed-responsive device, a divided connection for moving the valve which is actuated by the speed-responsive device, a lock for uniting the parts of the connection, a means for releasing the lock, and a means for separating the parts of the connection and shutting the valve.

6. In a governing mechanism, the combination of a valve, a speed-responsive device,

a divided connection for moving the valve 65 which is actuated by the speed-responsive device, a combined trigger and lock which normally unites the parts of the connection, and a means arranged to engage the trigger under certain conditions and release the lock and 70 permit the valve to move.

7. In a governing mechanism, the combination of a valve, a speed-responsive device, a divided connection for moving the valve, which is actuated by the speed-responsive device, 75 a bracket for supporting the connection, a lock normally holding the parts of the connection in a predetermined relation, and a spring for separating the parts of the connection and moving the valve when released by 80 the lock.

8. In a governing mechanism, the combination of a valve, a speed-responsive device, a divided connection for actuating the valve which is moved by the speed-responsive device, 85 a lock carried by one part of the connection and normally engaging another, a means for separating the parts of the connection when released by the lock, and an emergency-governor for releasing the lock. 90

9. In a governing mechanism, the combination of a valve, a speed-responsive device, a bell-crank lever comprising two principal parts for transmitting motion from the said device to the valve, a fulcrum which is common to said parts of the lever, a spring tending at all times to separate the parts of the lever, a lock for resisting the spring, and an emergency-governor for releasing the lock. 95

10. In a governing mechanism, the combination of a combined regulating and shut-off valve, a speed-responsive device, a divided lever for transmitting motion from the speed-responsive device to the valve, a universal connection between the lever and valve, a 105 spring normally tending to separate the parts of the lever, a lock normally uniting the parts of the lever, and a spring, the free end of which releases the lock under conditions of excess speed. 110

11. In a governing mechanism, the combination of a movable element, a valve which controls the action of the motive fluid on the movable element, a device responding to changes in speed of the movable element, 115 which tends to open and close the valve as the speed changes, and a second device normally inactive but which responds to abnormal speed changes and shuts said valve to cut off the supply of motive fluid to the movable 120 element.

12. In a governing mechanism, the combination of a movable element, a single valve which acts as a controlling and a shut-off valve, a speed-responsive device which tends 125 to open and close the valve as the speed of the moving element changes, and a means which, under abnormal conditions, closes the

valve irrespective of the position occupied by the speed-responsive device.

18. In a governing mechanism for motors, the combination of a valve which is adapted to shut off the supply of fluid to the motor when the speed exceeds a certain predetermined limit, a flat spring for actuating the valve which is rotated by the motor, and a support for the spring which also acts as a

stop to limit its outward movement due to centrifugal force.

In witness whereof I have hereunto set my hand this 17th day of February, 1905.

JOHN G. CALLAN.
